H. DERROUGH

CHIMNEY CONSTRUCTION

Filed Jan. 7, 1925

Harry Derrough
Inventor

By *Clarance O'Brien*

Attorney

UNITED STATES PATENT OFFICE.

HARRY DERROUGH, OF CHAMPAIGN, ILLINOIS.

CHIMNEY CONSTRUCTION.

Application filed January 7, 1925. Serial No. 1,042.

This invention relates to improvements in chimney constructions and has for its principal object to provide a simple and efficient means whereby the rooms of a building or an apartment may be heated by the waste heat passing upwardly through the chimney.

A further object of the invention is to provide a chimney of the above mentioned character, wherein the same is provided with a cold air inlet and a hot air outlet for cooperation with each of the rooms of a building or an apartment, whereby the cold air leaving each of the rooms will be heated by the products of combustion passing upwardly through a smoke flue arranged centrally within the chimney so that the heated air will be returned to the room.

A further object of the invention is to provide a chimney construction of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

The figure represents a vertical sectional view of the invention.

In the drawing wherein for the purpose of illustration is shown the preferred embodiment of my invention, the numeral 1 designates a chimney. Extending upwardly therefrom and arranged centrally therein is the smoke flue 2. The spacing of the smoke flue from the inner walls of the chimney 1 provides a hot air chamber 3 completely around the smoke flue.

The chimney 1 is constructed in such a manner as to provide closures for the hot air chamber at points between the hot air inlet and the adjacent cold air outlet, or more specifically each of the floor lines of the several rooms.

The chimney 1 is provided with cold air outlets 4 and hot air inlets 5 for cooperation with each of the rooms of the building or an apartment in the manner clearly illustrated in the drawing. The cold air outlets

being disposed adjacent the floor of each of the rooms while the hot air inlets are disposed adjacent the ceilings of each of the rooms. If desired, registers may be associated with each of the openings.

As the cold air in each of the rooms is discharged out through the openings 4, the same will pass upwardly into the air chamber 3 where it becomes heated by the combustible products passing upwardly through the smoke flue 2 and the heated air will then enter the rooms through the inlet openings 5. The arrows in the drawing indicate the manner in which the air circulates in connection with the chimney.

The provision of a chimney of the above mentioned character, will enable the rooms of a building or an apartment to be supplied with heat which is ordinarily wasted, thereby saving considerable expense in the burning of fuel necessary to heat the building or an apartment.

While I have shown the preferred embodiment of my invention, it is to be understood that various changes in the size, shape and arrangement of parts may be resorted to without departing from the spirit of the invention and the scope of the appended claim.

Having thus described my invention, what I claim is:—

In combination with a building, a chimney, a one-piece smoke flue extending upwardly and centrally therein whereby a hot air chamber is formed between the chimney and the smoke flue, said chimney having flared cold air openings communicating with the rooms of the building adjacent the floors thereof whereby the cold air in the rooms is discharged through the openings into the aforementioned hot air chamber, the chimney being further provided with flared hot air openings disposed adjacent the ceilings of the rooms whereby the heated air passing upwardly in the hot air chamber will pass through the last mentioned openings into the room, the portions of the chimney adjacent the respective floor lines of the rooms being built inwardly to provide a closure for the hot air chamber at each floor line.

In testimony whereof, I affix my signature.

HARRY DERROUGH.
